UNITED STATES PATENT OFFICE

ADOLF BEUTELSPACHER, OF PFORZHEIM, GERMANY

PIN

Application filed May 29, 1929, Serial No. 366,791, and in Germany February 2, 1928.

This invention relates to articles of jewelry of that class, such as brooches and the like, known as pins, and the objects of the invention are, first, to provide an improved construction of pin stem whereby the engaged portion of the fabric will be clamped between the pin body and the pin stem to hold the pin from tilting or sliding movements in any direction of the fabric; second, to provide a three-point tensioning action of a spring-clamp pin stem whereby the pin clamping action and the latching tension of its pointed end will be increased to prevent any possibility of the pin shifting on the fabric or of the pin stem being unlatched even when the pin is fastened upon very thin and sheer fabrics; third, to provide a spring-clamp pin stem whereby the pin may be securely clamped to ribbons or other fabrics without piercing the same; fourth, to provide for the use of a spring pin stem fastened to the pin body without soldering and without loss of spring temper due to a soldering action; and, finally, to generally improve the construction and increase the holding efficiency of the pin and to ensure greater security against its accidental release from the garment and loss.

The invention consists of the features of construction, combination and arrangement of parts, hereinafter fully described and claimed, reference being had to the accompanying drawing, in which:—

Figure 1 is a side elevation of a bar pin embodying my invention, and showing the pin stem unlatched and in its normal untensioned condition.

Figure 2 is a similar view, showing the pin stem in latched position.

Figure 3 is a back view of a portion of the pin body and showing the means for fastening the heel end of the pin stem thereto.

Figures 4 and 5 are cross-sections showing different forms of pin stems which may be employed.

Figure 6 is a view similar to Figure 2, disclosing a modified form of the invention.

Referring to the drawing, *a* represents the pin body, which may be in the form of a cuff pin, brooch, or of any other desired form or

shape, to which body a pin stem *b* is attached for connecting the article to the clothing of the wearer, or to any other support. The body *a* is provided with a longitudinally and transversely flat rear face *a'* at one end of which is disposed the usual catch or keeper *a²* to receive the point end of the pin stem, and at the other end of which is soldered or otherwise secured a retaining sleeve *a³* made of suitable sheet metal.

The pin stem *b* is of novel and improved construction and comprises a body portion *c* terminating in heel and point end portions *d* and *e*, which portions *d* and *e* are offset at an angle outwardly and rearwardly with respect to the body *c*. Between these two end portions *d* and *e* the pin stem body *c* is longitudinally bowed or curved in a direction toward the face *a'* of the pin body *a*, whereby the pin stem is adapted for a novel and efficient clamping action, as hereinafter described.

The heel end *d* of the pin stem has a return portion *f* which lies parallel with the plane of the body face *a'* and is adapted for engagement with the retaining sleeve *a³*. This return portion *f* is fitted in the sleeve when the bracelet parts are assembled and the sides of the sleeve are then subjected to a crimping action at a plurality of spaced points, as indicated at *g*, to provide instruck projections, by means of which the return portion of the heel end of the pin is permanently fastened to the pin body *a* without the necessity of hitting the pin stem or directly soldering any part thereof to the pin body, thereby avoiding all liability of reducing the temper of the spring material of which the pin stem is made.

The degree of bow or curvature of the body portion of the pin stem is such that when the pin stem is closed and its point end *e* engaged with the keeper *a²*, the stem will be placed under an intermediate main tension, under which it is straightened out to a flat or substantially flat condition, as shown in Figure 2, and thus flatly engages the surface *a'* of the pin body *a* or in any fabric interposed therebetween throughout the entire length of the pin stem body between its offset

portions *d* and *e*. It will be understood, of course, that the pin stem may be used for fastening the pin to an article of clothing or piece of fabric in the usual way, that is by passing the pin through the fabric and engaging its point end with the keeper α^2 , or that, when it is not desired to pierce the fabric, the pin may be simply closed to bind the fabric without piercing it between it and the pin body face α' . Where the pin stem is used to both pierce and clamp the fabric, it is obvious that the pin will be held firmly and prevented from turning or tipping on the pin stem out of proper position, the double engagement enabling the pin to be secured to even the finest and most delicate fabrics without injury to the latter and without shifting out of its proper display position. The novel structure of the pin stem which adapts it for a clamping action throughout its length enables the pin to be secured to fabrics without piercing the latter, such use being particularly advantageous in applying the pin to ribbon supports of various widths so firmly as to obviate any liability of casual displacement of the pin or its possible loss. To increase its clamping efficiency the pin stem may be transversely flat, as shown in Figure 4, so as to provide a flat bearing face c' , or, as shown in Figure 5, it may be of half round form so as to provide it with at least an inner flattened face c^2 . However, the pin stem may be made of circular cross-section throughout, if desired.

In the operation of closing the pin stem, the portion of the stem body adjacent the heel end *d* first comes in contact with the pin body α , so that the offset heel portion *d* is placed under tension, the bowed body portion of the pin stem then progressively comes into contact with the pin body and is flattened out and placed under tension, and finally the pin portion *e* of the pin stem is forcibly brought into engagement with the keeper α^2 , to latch the pin stem, in which action it will be placed under tension, so that when the pin stem is closed its flattened body portion will clamp the fabric by its own tension, throughout its length, and by the auxiliary tension of each of the end portions *d* and *e*, so that a maximum firmness and security of clamping engagement is obtained. By securing the pin stem to the pin body without soldering a pin stem of maximum spring temper may be produced and applied without its temper being impaired, so that a clamping pin stem of maximum efficiency will be furnished.

In the modified form of the invention shown in Figure 6, the spring pin stem is shown as having an offset heel end d' which is integral with the pin body α^4 . This construction may be used in the manufacture of elongated rod-like brooches, stick pins, hat ornaments, lodge pins, etc., where the article

is of restrictive width and both main parts thereof may be readily made from a single kind of material and as a unitary article of manufacture.

Having thus fully described my invention, I claim:

1. A pin comprising a pin body, a keeper carried thereby, and a spring pin stem having a heel end secured to the pin body, a body portion bowed longitudinally toward the rear face of the pin body, and a point-end engageable with the keeper to hold the pin closed, said heel and point ends being offset at an angle to and rearwardly from the bowed body of the pin stem to provide end tensioning portions, and said body portion of the pin stem being bowed to such a degree as to be flattened substantially throughout its length when in closed position under its pressure against the pin body.
2. A pin comprising a pin body, a keeper and a retainer upon the rear face of the pin body, and a spring pin stem having a longitudinally bowed body portion and heel and point ends bent outwardly and rearwardly at an angle to the body portion, the said point end being adapted for engagement with the keeper to hold the pin closed and the said heel end being provided with a return portion physically interlocked with the retainer, and the said body portion being bowed continuously between the heel and point ends and adapted to be flattened out under its pressure against the pin body when the pin stem is closed.
3. A pin comprising a pin body, and a spring pin stem, the latter having a heel end secured to the pin body, a point end adapted to be engaged with the body to hold the pin stem closed, and a bowed body portion, the said heel and tail ends being offset at an angle to the body portion to provide therewith central and end spring portions adapted to be tensioned when the pin stem is closed.

ADOLF BEUTELSPACHER.
